UNITED STATES PATENT OFFICE.

WILLIAM HENRY CLAY, OF EUSTIS, FLORIDA.

BOW-FACING OAR.

1,406,932.

Specification of Letters Patent. Patented Feb. 14, 1922.

Application filed December 8, 1920. Serial No. 429,252.

To all whom it may concern:

Be it known that I, WILLIAM HENRY CLAY, a citizen of the United States, residing at Eustis, in the county of Lake and State of Florida, have invented certain new and useful Improvements in Bow-Facing Oars; and I do hereby declare the following to be a full, clear, and exact description of the invention, such as will enable others skilled in the art to which it appertains to make and use the same.

This invention relates to rowing oars generally, especially the type termed bow-facing, and is an improvement upon that forming the subject matter of Letters Patent granted to me September 14, 1920, No. 1,353,027.

The invention has for its object particularly to facilitate the submergent or dipping action of the oar and its withdrawal from the water, in other words, to effect this in perpendicular or straight lines, and also to provide for readily lifting the oar with facility to the gunwale or thereabove for greater convenience and ease to the rower.

The invention also has for its object to improve the structural features thereof and to effect the ready installment of the same for use.

Further objects of the invention, together with the foregoing will be apparent from the following description of the construction, arrangement and operation of the same.

The invention therefore consists of certain instrumentalities and features of construction substantially as hereinafter more fully set forth and pointed out in the claims.

The accompanying drawing illustrates the preferred embodiment of one form of my invention, wherein it will be understood that various changes and modifications thereof that relate to the detailed construction and arrangement of parts may be made without departing from the spirit or scope of the invention as covered by the claims, and in which drawings:

Figure 1 is a side view of my invention as applied to the boat-gunwale.

Fig. 2 is a plan view of the same.

Fig. 3 is an inverted view, partially fragmental, showing more particularly an oar, including the attaching means therefor to the gunwale.

Figure 4 is a sectional view taken on the line 4—4 of Figure 1.

Fig. 5 is a detailed horizontal section taken on the line 5—5 of Fig. 1.

Fig. 6 is an inverted plan view, showing more fully the character of the resilient or automatically retained pins of the guide-rail applied to the gunwale for the connection therebetween and the paddle.

As characteristic features of my present improvements, I provide a suitable guide-rail or rod 1 upon the gunwale 2 of a boat, said guide-rail or rod having downwardly turned portions or terminals extending through socket-castings 3 secured to the gunwale, preferably as shown or otherwise, said down-turned terminals of said rail or rod passing through orifices 3^a in the gunwale and projecting therebelow. A preferably resilient or automatically retained pin 4, suitably confined, against displacement, to the gunwale by a chain or otherwise, is provided for insertion through a transverse orifice 3^b in each rod-terminal for the retention of the rail 1 in place, the resilient portion or terminal of said pin being bent or curved 80 so as to shoulder, as it were, transversely upon each of said rod-terminals and thus prevent its inadvertent displacement.

The oar proper and its handle, designated as 5, 5^a, respectively, are each secured to, and between parallel clamping angular members 6, 6^a, the latter facing, oppositely at obtuse angles, each other, as shown, with the terminals of their angular portions converging and pivoted upon the rod or rail 1 90 by a common, or the same, pivot 7, said pivot being preferably in the form of a pin freely sleeved as at 7^a upon the rod or rail 1, said pin or pivot having inserted transversely therethrough preferably a cotter-pin 7^b for 95 the retention of the angular members 6, 6^a upon said pin. The angular members 6^a are suitably conformed in transverse section and secured to the blade and handle members 5, 5^a, respectively, and have link-connections 8, 8 with a sleeve 9 mounted to freely slide and turn upon the rod or rail 1, thus providing, by suitably operating the handle 5^a, for actuating the blade so that the blade is adapted to perform its submergent 100 action or stroke also to perform its opposite stroke, or withdrawal out of submergence, along straight lines. This operation is due to the fact that the angular members 6^a of the blade and handle members 5, 5^a, are adapted to 110 not only have a longitudinal or endwise sliding movement upon the rod or rail 1, but

also to be rotated horizontally whereby, it is apparent, that the oar proper, or its blade, is adapted to be disposed in a plane or position not only parallel with the axis or length 5 of the boat but also be disposed in a plane above the gunwale. This arrangement, it will be observed, permits the handle member 5^a to be brought into position to be conveniently manipulated by the operator or rower, 10 thereby promoting ease and facility in effecting the rowing operation.

I claim:

1. In a device of the type described, the combination of a rail-member secured to the 15 gunwale of a boat, an oar-blade and its handle, a slidable and rotatable member arranged on said rail-member, means effecting connection of said blade and handle with said slidable and rotatable member, a rotatable member arranged on said rail-member, said oar-blade and handle having terminals angled laterally towards said slidable and 20 rotatable member and pivotally connected to said rotatable member.
2. In a device of the type described, the combination of a rail-member secured to the gunwale of a boat, an oar blade and its handle, a slidable and rotatable member arranged on said rail-member, means effecting 25 connection of said blade and handle with said slidable and rotatable member, a rotatable member arranged on said rail-member, 30 said oar-blade and handle having terminals angled laterally towards said rotatable and slidable member and pivotally connected to said rotatable member, and resilient means for retaining said rail-member to the gunwale.

said oar-blade and handle having terminals obtuse-angled laterally towards said slid- 35 able and rotatable member and pivotally connected to said rotatable member.

3. In a device of the type described, the combination of a rail-member secured to the gunwale of a boat, an oar blade and its handle, a slidable and rotatable member ar- 40 ranged on said rail member, a rod effecting connection of said blade and handle with said slidable and rotatable member, a rotatable member arranged on said rail-member, 45 said oar-blade and handle having terminals angled laterally towards said rotatable and slidable member and pivotally connected to said rotatable member.

4. In a device of the type described, the combination of a rail-member secured to the gunwale of a boat, an oar-blade and its handle, a slidable and rotatable member ar- 50 rangle on said rail-member, means effecting connection of said blade and handle with said slidable and rotatable member, a rotatable member arranged on said rail-member, 55 said oar-blade and handle having terminals angled laterally towards said rotatable and slidable member and pivotally connected to said rotatable member, and resilient means 60 for retaining said rail-member to the gunwale.

In testimony whereof, I affix my signature.
WILLIAM HENRY CLAY.
